UNITED STATES PATENT OFFICE.

ORIN J. ZOOK AND JOHN C. MARSHALL, OF BUTTE, MONTANA.

MINE-CAR.

1,358,678.

Specification of Letters Patent.

Patented Nov. 9, 1920.

Application filed June 7, 1920. Serial No. 387,023.

To all whom it may concern:

Be it known that we, ORIN J. ZOOK and JOHN C. MARSHALL, citizens of the United States, residing at Butte, in the county of 5 Silver Bow and State of Montana, have invented certain new and useful Improvements in Mine-Cars, of which the following is a specification, reference being had to the accompanying drawings.

10 This invention relates to certain improvements in mine cars and has relation more particularly to a car of this general character embodying a tilting or dumping body, and it is an object of the invention to provide a device of this general character with 15 novel and improved means whereby the body may be effectively locked in its lowered or operative position yet readily and conveniently released when it is desired to tilt 20 the same to effect a dumping operation.

Another object of the invention is to provide a novel and improved car of this general character including a tail gate which is effectively locked in closed position when the 25 body is in its lowered or normal position but which is automatically released when the body is tilted.

An additional object of the invention is to provide a novel and improved car of this 30 general character wherein none of the mechanism for locking the body in its lowered or normal position or for locking the tail gate projects outwardly of the body of the car.

35 The invention consists in the details of construction and in the combination and arrangement of the several parts of our improved car whereby certain important advantages are attained and the device rendered simpler, less expensive and otherwise 40 more convenient and advantageous for use, as will be hereinafter more fully set forth.

The novel features of our invention will hereinafter be definitely claimed.

45 In order that our invention may be the better understood, we will now proceed to describe the same with reference to the accompanying drawings, wherein:

Figure 1 is a fragmentary view partly in 50 side elevation and partly in section illustrat-

ing a dumping car constructed in accordance with an embodiment of our invention with the body in its lowered or normal position;

Fig. 2 is a fragmentary view in front elevation of the car as herein disclosed; 55

Fig. 3 is a fragmentary view in rear elevation of the car as herein embodied with the door or tail gate in closed position;

Fig. 4 is an enlarged fragmentary view 60 in top plan of the frame carrying the holding jaws and the annular member or ring coacting with the jaws for holding the same in working position;

Fig. 5 is a longitudinal vertical sectional view taken through the structure as illustrated in Fig. 4; 65

Fig. 6 is a fragmentary view partly in horizontal section and partly in top plan of the locking means coacting with the door or tail gate, a portion of the casing being 70 indicated by dotted lines;

Fig. 7 is a longitudinal vertical sectional view taken through the structure as illustrated in Fig. 6 with certain of the parts in elevation and a portion of the tail gate being 75 included and a part indicated by dotted lines;

Fig. 8 is a view in front elevation of the locking means as illustrated in Figs. 6 and 7 unapplied; and 80

Fig. 9 is a fragmentary sectional view partly in transverse section and partly in elevation illustrating in detail means herein embodied whereby the latch plate may be manually operated. 85

As disclosed in the accompanying drawings, F denotes the frame of our improved car of requisite length and which in cross section is substantially in the form of an inverted U. The longitudinal marginal portions of the frame F are defined by the outstanding flanges 1, provided at predetermined points therealong with the underhung bearings 2 for the axles 3. Mounted in the conventional manner upon the end portions of each of the axles 3 are the wheels 4, herein disclosed of a flanged type, for traveling over a trackway. 90

B denotes the body of the car and depending from the bottom 5 thereof rear- 95

wardly of its longitudinal center is a pair of depending bearings 6 coacting with a shaft or rod 7, also disposed through the upstanding bearings 8. The bearings 8 are carried by the rear portion of the plate 9 supported upon the frame F but in spaced vertical relation thereto. The rod 7 serves as a fulcrum about which the body B turns when it is desired to tilt such body to effect 10 a dumping operation.

Suitably secured to the under surface of the bottom 5 of the body B adjacent its forward end is a transversely disposed bolster 10 substantially U-shape in form. The base 15 or intermediate portion 10^a of the bolster rests upon the frame F when the body B is in its lowered or normal position.

C denotes a frame substantially oblong in form and having its upper margins provided 20 with the outstanding flanges 11 perpendicular thereto and said flanges 11 are adapted to be secured to the under surface of the frame F in any desired manner, as by bolts or the like. The frame C, when applied, depends from the frame F at a point in advance of but in close proximity to the front truck or axle 3 or more particularly immediately below the portion of the frame F with which the intermediate portion 10^a of 25 the bolster 10 engages and also preferably at the transverse center of said frame F. The portion of the frame F within the area defined by the applied frame C is provided with a circular opening 12 through which is 30 adapted to extend a depending part or member 14 arranged at substantially the longitudinal center of the portion 10^a of the bolster 10 and preferably integral therewith. The part or member 14 is preferably in the 35 form of a truncated cone although we do not wish to be understood as limiting ourselves to this exact formation. Suitably secured to the axial center of the lower end of the part or member 14 is a depending 40 shank 15 provided at its lower or free end with a head 16 parti-spherical in form with its upper or inner portion 16^a arranged on a taper. The tapered portion 16^a is concentric to the axial center of the shank 15 45 and it is preferred that the parti-spherical portion 16^b of the head 16 be in excess of a semi-sphere in a vertical direction.

Disposed through the side members 17 of the frame C at opposite sides of the longitudinal center thereof and bridging the 55 space between said side members 17 are the pintle members or bolts 18. Each of the bolts 18 is provided at one end with a head 19 adapted to substantially contact with the 60 outer face of the forward or outer side member 17 and the opposite end portion of said bolt or member 18 extends beyond the inner or rear side member. Disposed through said 65 extended portion of the member or bolt 18 is a locking pin 20 whereby said bolt is effec-

tively maintained in applied position yet capable of being removed or applied in accordance with the requirements of practice.

Each of the members or bolts 18 is loosely directed through the lower portion of a jaw 70 or dog D and which dog has swinging movement about the member or bolt 18 in a direction transversely of the body B.

The jaws or dogs D are alined in a direction transversely of the body B and the opposed faces thereof are provided with the recesses or sockets 21 which are adapted to snugly receive the head 16 of the shank 15 when said jaws are at the limit of their movements one toward the other. Each of 75 the recesses or sockets 21 is of a form substantially identical with a lateral path of the head 16 and therefore embodies a bevel portion 21^a which, when the same is in operative engagement with the head 16, overlies the bevel portion 16^a of the head 16. By this means, it will be readily seen that when the jaws or dogs D are at the limit of 80 their inward movement, the head 16 is enclosed thereby whereby said jaws or dogs D 85 effectively lock the body B against tilting movement with respect to the frame F.

The upper or top faces of the jaws or dogs D are provided with the substantially semi-circular and upstanding shoulders 22 around 95 which is adapted to be positioned an annular member or ring 24 and said ring or member 24, when so positioned, serves to hold the jaws or dogs D against separating movement and in locking engagement with the 100 head 16.

The annular member or ring 24 is carried by and preferably integrally formed with an extremity of an elongated and forwardly directed arm or bar 25 disposed upwardly on 105 a predetermined incline with respect to the annular member or ring 24. The forward or free end portion of the bar 25 extends between a pair of lugs 26 depending from the frame F and is pivotally engaged therewith 110 through the instrumentality of the pin 27, or the like. By this means, the annular member or ring 24 is capable of vertical movement so that the same may be raised or elevated sufficiently to free the shoulders 22 115 in order to permit the jaws or dogs D to separate to release the head 16 when it is desired to tilt the body B to effect a dumping operation. When the body B is returned to its normal position, the head 16, as it 120 enters between the jaws or dogs D, will automatically swing said dogs or jaws inwardly and at the proper moment, the annular member or ring 24 will drop by gravity to surround the shoulders 22 to hold said jaws or dogs D in locking position with respect to the head 16.

The side members 17 of the frame C have their central portions cut-away, as at 23, to 125 permit the requisite application of the an- 130

nular member 24 and sufficiently to permit the requisite functioning of said member or ring.

Depending from the central portion of the inner or rear side member 17 of the frame C is a pair of spaced arms or brackets 28 between which extends an upstanding lug 29 carried by the pedal 30. The lug 29 is pivotally engaged with the arms or brackets 28 by the pin 31, or the like, and whereby the pedal 30 is supported for swinging movement in a vertical direction. The pedal 30 extends rearwardly and longitudinally of the frame F and can be readily depressed manually, as by the foot of a person, when required. The forward or pivoted end of the pedal 30 is continued by an upwardly disposed arm or extension 32 which underlies the bar 25 and has contact therewith. When the pedal 30 is depressed, the extension or arm 32 swings upwardly and lifts the bar 25 to free the annular member or ring 24 and from the shoulders 22 so that the body B is free to be tilted with respect to the frame F.

The rear end portion of the plate 9 is provided with an upstanding bolster 33 with which the bottom 5 of the body B also engages when in its normal position and whereby the weight of the load is effectively distributed upon the frame F.

T denotes a tail gate or door coacting with the rear end of the body B and having its upper side portions pivotally engaged with the upper portions of the body B so that said door or tail gate T, when moving into an open position, swings upwardly. Suitably secured to the lower marginal portion of the door or tail gate T, at substantially its center, is a strap 34. The lower end of the strap 34 is continued by a bolt 35 extending beyond the lower margin of the door or gate T and which is adapted to be engaged by the jaws 36 to hold the door or gate T in its lowered or closed position.

E denotes an elongated casing secured to the rear portion of the bottom 5 of the body B, one end portion of said casing E extending beyond the rear end of said bottom 5. The extended portion of the casing E is provided with a recess 37 to receive the bolt 35 when the door or gate T is in its lowered or closed position.

The casing E is substantially U-shaped in cross section and its longitudinal margins are defined by the outstanding flanges 38 which are suitably anchored, as at 39, to the bottom 5 of the body B. The outer or rear end portions of the side members 40 of the casing E immediately adjacent the flanges 38 are provided with the open slots 41 and adjacent the lower marginal portion of each of said slots 41 is an outstanding ear 42. Each of the jaws 36 is arcuate in form and extends between an ear 42 and a

flange 38 and is pivotally held therebetween by the pin 43, or the like. Said jaw has swinging movement through the slot 41 so that the same may be readily and effectively engaged with the bolt 35.

Arranged within the casing E for rectilinear movement therein is a plate or bolt 44 provided at its forward end with an upstanding block 45. The forward portion of the block 45 has its side portions cut away, as at 46, to provide cam elements 47 coacting with the inwardly directed extensions or tails 48 provided at the pivoted end portions of the jaws 36 so that upon outward movement of the plate or bolt 44, the jaws 36 will be separated to disengage from the bolt 35. When the door drops or returns to its lowered or closed position, the contact of the bolt 35 with the adjacent end of the plate or bolt 44 will move said plate or bolt inwardly and thereby result in an inward swinging movement of the jaws 36 to properly engage the bolt 35 to hold the door or gate T in its lowered or closed position. The inner or forward end portion of the plate or bolt 44 is provided with an upstanding block or flange 49 provided with an opening 50 in alinement or registering with an opening 51 provided in the inner or closed end 52 of the casing E. The base portion of the opening 50 is continued by longitudinally disposed groove or channel 53 provided in the upper face of the plate or bolt 44 and the inner end 54 of said groove or channel constitutes a stop. The plate or bolt 44, at a point inwardly of but in close proximity to the lock or flange 49, as at 55, is of increased thickness and the inner face of said portion 55 affords a shoulder 56 also serving as a stop. The portion 55 also has disposed therethrough the groove or channel 53 hereinbefore referred to. The upper surface or face 57 of the plate or bolt 44 between the block 45 and the shoulder or stop 56 is disposed on a predetermined incline throughout its entire length downwardly and toward the shoulder or stop 56.

Contacting with the surface or face 57 of the plate or bolt 44 is the free end portion 115 of the latch plate 58 extending in a direction longitudinally of the plate or bolt 44. The forward end portion of the latch plate 58 is pivotally supported by the pin 59, or the like, disposed transversely through said end portion of the latch plate and supported by the side walls 40 of the casing E adjacent the upper edges thereof and at a point inwardly of but in close proximity to the block 45 when the plate or bolt 44 is at the limit of its inward or retracted movement. The inner or free end portions of the latch plate 58 contacts by gravity with the face or surface 57 of the bolt or plate 44 and when in contact with the shoulder or stop 56 130

holds the plate or bolt 44 against forward movement. Extending through the registering or aligned openings 50 and 51 is an end portion of a releasing rod 61 which is adapted to travel within the groove or channel 53. The rod 61 is of desired length and extends inwardly or forwardly of the body B and terminates in a depending extension or arm 62 in contact with the rear end of the plate 9 so that when the body B is tilted to effect a dumping operation, the releasing rod 61 will be forced rearwardly of the body B and inwardly of the casing E. An end of the rod 61 within the casing E is beveled, as at 15 63, so that as the rod 61 moves inwardly of the casing E, the same will ride under the latch plate 58 and release the same from the stop or shoulder 56 and disengage said plate from said shoulder so that the plate or bolt 20 44 is free to move rearwardly. As the rod 61 continues to move inwardly of the casing E, it comes into contact with the stop or shoulder 54 and the continued movement of said rod 61 forces the bolt or plate 44 in a 25 direction toward the door or tail gate T resulting in the jaws 36, in the manner hereinbefore set forth, disengaging the bolt 35 so that the door or gate T is free to open and to maintain said jaws 36 open so that the 30 bolt 35 may enter between said jaws when the tail gate closes automatically under its own weight as the car is turned back to normal position. In practice, we find it of particular advantage to have the rod 61 engage 35 the stop or shoulder 54 when the forward end portion of the body B has been lifted about four inches.

It will also be understood that when the latch plate 58 is released, the plate or bolt 44 is free to move outwardly and, therefore, the bolt 35 pressing outward against the inclined inner faces of the jaws 36 under its own weight and the weight of the material in the car bearing on the tail gate during the 45 tilting will spread the jaws 36 apart, drawing the plate 44 forward so that the bolt 35 will automatically, by the weight of the door and the material, escape from the jaws and permit the tail gate T to swing open.

Extending laterally from the inner or working end portion of the latch plate 58 is an arm 63 which projects exteriorly of the casing E through an opening 64 provided in a side member 40 of the casing E. The 55 extended portion of the arm 63 is provided with a depending arm 65 which provides means whereby the latch plate 58 may be manually raised when the occasions of practice may so require. It is to be particularly noted that none of the mechanism for locking the body B in its lowered or normal position or the mechanism coacting with the door or tail gate T extends beyond the body B so that the possibility of said mechanisms

being accidentally operated is substantially 65 eliminated and injury thereby to persons during the transit of the car is prevented.

From the foregoing description, it is thought to be obvious that a car constructed in accordance with our invention is particularly well adapted for use by reason of the convenience and facility with which it may be assembled and operated, and it will also be obvious that our invention is susceptible of some change and modification without departing from the principles and spirit thereof, and for this reason we do not wish to be understood as limiting ourselves to the precise arrangement and formation of the several parts herein shown in carrying out our invention in practice except as herein-after claimed.

We claim:

1. A dumping car comprising, in combination, a truck frame, a body mounted thereon for tilting movement, a headed member depending from the body, pivoted jaws carried by the truck frame to receive the headed member therebetween, a locking member coacting with the jaws for holding the same in operative engagement with the headed member, said locking member including an arm pivotally engaged with the truck frame, and a manually operated member carried by the frame and engageable with the arm of the locking member to free said locking member from the jaws. 85

2. A dumping car comprising, in combination, a truck frame, a body mounted thereon for tilting movement, a headed member depending from the body, pivoted jaws carried by the truck frame to receive the headed member therebetween, a locking member coacting with the jaws for holding the same in operative engagement with the headed member, said locking member including an arm pivotally engaged with the truck frame, and a pedal pivotally supported by the truck frame, said pedal being provided with an extension for contact with the arm of the locking member, said extension, upon movement of the pedal in one direction, moving the arm of the locking member to free said locking member from the jaws. 100

3. A dumping car comprising, in combination, a truck frame, a body mounted thereon for tilting movement, a casing depending from the frame, rocking jaws supported within the casing, a headed member depending from the body and extending between the jaws when the body is in its lowered position, said headed member moving the jaws into locking engagement therewith when the body is in its lowered position, a member for holding the jaws in locking engagement 115 with the headed member, and means carried by the casing for releasing the holding member from the jaws. 120

125

4. A dumping car comprising, in combination, a truck frame, a body mounted thereon for tilting movement, a headed member depending from the body, relatively movable jaws supported by the frame, said headed member extending between the jaws and held thereby when the body is in its lowered position, each of said jaws being provided with an outstanding shoulder, a member surrounding the shoulders of the jaws when said jaws are in locking engagement with the headed member to hold said jaws against separating movement, and means for freeing said member from the shoulders to permit the jaws to separate. 15
5. A dumping car comprising, in combination, a truck frame, a body mounted thereon for tilting movement, a gravity closing tail gate carried by the body and supported for swinging movement, relatively movable jaws carried by the body and coacting with the gate for holding the gate in closed position, and automatic means operable upon tilting movement of the body in one direction to separate the jaws to release the gate. 20
6. A dumping car comprising, in combination, a truck frame, a body mounted thereon for tilting movement, a swinging end gate carried by the body, a bolt carried by said end gate, a pair of relatively movable jaws carried by the body and automatically engaging the bolt when the gate is in closed position to hold said gate against opening movement, and automatic means operable upon tilting movement of the body in one direction to separate the jaws to release the gate. 35
7. A dumping car comprising, in combination, a truck frame, a body mounted thereon for tilting movement, a swinging end gate for the body, a bolt carried by the gate, a casing secured to the body, swinging jaws carried thereby and engaging the bolt when the door is closed to hold the door against opening movement, and a movable plate within the casing, said plate and jaws being provided with coacting means whereby the jaws are caused to separate upon movement of the plate in one direction. 40
8. A dumping car comprising, in combination, a truck frame, a body mounted thereon for tilting movement, a swinging end gate for the body, a bolt carried by the gate, a casing secured to the body, swinging jaws carried thereby and engaging the bolt when the door is closed to hold the door against opening movement, a movable plate within the casing, said plate and jaws being provided with coacting means whereby the jaws are caused to separate upon movement of the plate in one direction, and means for locking said plate against such movement. 45
9. A dumping car comprising, in combination, a truck frame, a body mounted
- thereon for tilting movement, a swinging end gate for the body, a bolt carried by the gate, a casing secured to the body, swinging jaws carried thereby and engaging the bolt when the door is closed to hold the door against opening movement, a movable plate within the casing, said plate and jaws being provided with coacting means whereby the jaws are caused to separate upon movement of the plate in one direction, means for locking said plate against such movement, a movable plate within the casing, said plate and jaws being provided with coacting means whereby the jaws are caused to separate upon movement of the plate in one direction, means for locking the plate in one direction, means for locking said plate against such movement, and automatic means for rendering said last named means inoperative. 70
10. A dumping car comprising, in combination, a truck frame, a body mounted thereon for tilting movement, a swinging end gate for the body, a bolt carried by the gate, a casing secured to the body, swinging jaws carried thereby and engaging the bolt when the door is closed to hold the door against opening movement, a movable plate within the casing, said plate and jaws being provided with coacting means whereby the jaws are caused to separate upon movement of the plate in one direction, means for locking said plate against such movement, and automatic means for rendering said last named means inoperative. 75
11. A dumping car comprising, in combination, a truck frame, a body mounted thereon for tilting movement, a gravity closing tail gate carried by the body and supported for swinging movement, relatively movable jaws carried by the body and coacting with the gate for holding the gate in closed position, and automatic means operable upon tilting movement of the body in one direction to separate the jaws to release the gate, said jaws automatically returning to locking position when the gate returns to its closed position. 80
12. A dumping car comprising, in combination, a truck frame, a body mounted thereon for tilting movement, a tail gate carried by the body and supported for swinging movement, relatively movable jaws carried by the body and automatically engaging the tail gate when the gate is in closed position to hold said gate against opening movement, means for maintaining said jaws in such position, and automatic means operable upon tilting movement of the body in one direction to render said last named means inoperative to permit the jaws to separate to release the gate. 85
13. A dumping car comprising, in combination, a truck frame, a body mounted thereon for tilting movement, a tail gate carried by the body and supported for swinging movement, relatively movable jaws carried by the body and automatically engaging the tail gate when the gate is in closed position to hold said gate against 90
14. A dumping car comprising, in combination, a truck frame, a body mounted thereon for tilting movement, a tail gate carried by the body and supported for swinging movement, relatively movable jaws carried by the body and automatically engaging the tail gate when the gate is in closed position to hold said gate against 95
15. A dumping car comprising, in combination, a truck frame, a body mounted thereon for tilting movement, a tail gate carried by the body and supported for swinging movement, relatively movable jaws carried by the body and automatically engaging the tail gate when the gate is in closed position to hold said gate against 100
16. A dumping car comprising, in combination, a truck frame, a body mounted thereon for tilting movement, a tail gate carried by the body and supported for swinging movement, relatively movable jaws carried by the body and automatically engaging the tail gate when the gate is in closed position to hold said gate against 105
17. A dumping car comprising, in combination, a truck frame, a body mounted thereon for tilting movement, a tail gate carried by the body and supported for swinging movement, relatively movable jaws carried by the body and automatically engaging the tail gate when the gate is in closed position to hold said gate against 110
18. A dumping car comprising, in combination, a truck frame, a body mounted thereon for tilting movement, a tail gate carried by the body and supported for swinging movement, relatively movable jaws carried by the body and automatically engaging the tail gate when the gate is in closed position to hold said gate against 115
19. A dumping car comprising, in combination, a truck frame, a body mounted thereon for tilting movement, a tail gate carried by the body and supported for swinging movement, relatively movable jaws carried by the body and automatically engaging the tail gate when the gate is in closed position to hold said gate against 120
20. A dumping car comprising, in combination, a truck frame, a body mounted thereon for tilting movement, a tail gate carried by the body and supported for swinging movement, relatively movable jaws carried by the body and automatically engaging the tail gate when the gate is in closed position to hold said gate against 125
21. A dumping car comprising, in combination, a truck frame, a body mounted thereon for tilting movement, a tail gate carried by the body and supported for swinging movement, relatively movable jaws carried by the body and automatically engaging the tail gate when the gate is in closed position to hold said gate against 130

opening movement, means for maintaining said jaws in such position, and automatic means operable upon tilting movement of the body in one direction to render said last 5 named means inoperative to permit the jaws to separate to release the gate, said last named means also operating automatically to hold the jaws in separated relation to per-

mit automatic closing and locking of the tail gate as the body tilts in the opposite direction. 10

In testimony whereof we hereunto affix our signatures.

ORIN J. ZOOK.
JOHN C. MARSHALL.
